CLAIM

The ornamental design for a stretchable polyester-cotton blend ice pack wrap, as shown and described.

DESCRIPTION

FIG. 1 is a perspective front view of the stretchable polyester-cotton blend ice pack wrap;

FIG. 2 is a perspective front view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings illustrate portions of the stretchable polyester-cotton blend ice pack wrap that form no part of the claimed design.
